(57) **CLAIM**

The ornamental design for combined storage and display container for a toy car, as shown and described.

DESCRIPTION

FIG. 1 is a perspective view of the storage and display container for a toy car showing my new design in open condition;

FIG. 2 is a front view thereof;

FIG. 3 is a left side view thereof;

FIG. 4 is a right side view thereof;

FIG. 5 is a top plan view thereof;

FIG. 6 is a rear view thereof;

FIG. 7 is a bottom plan view thereof;

FIG. 8 is a perspective view thereof in closed condition;

FIG. 9 is a perspective view of a second embodiment of the storage and display container for a toy car showing my new design in open condition;

FIG. 10 is a perspective view thereof in closed condition;

FIG. 11 is a front view thereof in open condition;

FIG. 12 is a left side view thereof;

FIG. 13 is a right side view thereof;

FIG. 14 is a top plan view thereof;

FIG. 15 is a rear view thereof; and,

FIG. 16 is a bottom plan view thereof.
